August J. Carlson
Inventor

By his Attorney

Frank Warren

UNITED STATES PATENT OFFICE.

AUGUST J. CARLSON, OF TACOMA, WASHINGTON, ASSIGNOR OF ONE-HALF TO ANDREW NILAND, OF SEATTLE, WASHINGTON.

HAIR-CLIPPER.

1,397,721.

Specification of Letters Patent. Patented Nov. 22, 1921.

Application filed March 3, 1919. Serial No. 280,485.

To all whom it may concern:

Be it known that I, AUGUST J. CARLSON, a subject of the Government of Finland, residing at Tacoma, in the county of Pierce 5 and State of Washington, have invented a certain new and useful Improvement in Hair-Clippers, of which the following is a specification.

My invention relates to improvements in 10 hair clippers and the object of my invention is to provide a hair clipper that embodies a cheap, efficient and substantial mechanism by which they may be attached to an electric motor in such manner that the hair clippers 15 will be driven thereby.

A further object is to provide a hair clipper wherein the working parts are housed in such manner as to exclude hair therefrom and to provide mechanism that 20 will impart a relatively long cutting stroke to the hair clippers.

I accomplish these objects by devices illustrated in the accompanying drawings, wherein—

25 Figure 1 is a view in side elevation of a motor casing having hair clippers constructed in accordance with my invention installed thereon;

Fig. 2 is a view in horizontal cross-section 30 on broken line 2, 2 of Fig. 1; and

Fig. 3 is a view in vertical mid-section on broken line 3, 3 of Fig. 2, a fragment of the motor and motor shaft being shown.

Referring to the drawings, throughout 35 which like reference numerals indicate like parts, the numeral 5 designates a casing of well known form of construction wherein is disposed an electric motor, not shown, that is arranged to rotate a main shaft 6 having 40 a smaller eccentric driving shaft 7 rigidly connected therewith and projecting from the end thereof.

The motor casing 5 is provided with a suitable handle 8 through which extends a cable 10 by which electric current is conducted to the motor and is further provided with a thumb switch 11 for starting and stopping the speed of the same.

50 The hair clippers comprise a base member 12 which is provided on the front edge with teeth 14 and arranged to have an upper cutting member 15 reciprocably mounted there-

on, the cutting member 15 having teeth 16 on the front edge thereof that move transversely over the teeth 14 of the base member. 55

The cutting member 15 is provided with two longitudinally extending slots 17 which are arranged to fit over the upper end of stud pins 18 that are fixed to the base member 12 and by which the cutting member is 60 guided for reciprocation.

The base member 12 is secured by screws 20 to the bottom 21 of a housing, the said housing comprising the side walls 22 and 23, a rear wall 24 and a top wall 25 whereon 65 is provided a socket 26 that is adapted to fit over the lower end 27 of the motor casing 5.

The lower end 27 of the motor casing 5 is preferably of reduced size whereby a shoulder 29 is formed and the socket 26 is arranged to fit against the shoulder 29 and be secured to the end 27 by a set screw 28.

The front edge of the housing cover 25 projects well forward over the clippers, as shown in Figs. 1 and 3, and the front side 75 of such housing is closed by a plate 31 of spring metal that is secured at its top edge to the top portion 25 of the housing and is arranged to have its bottom edge rest with a light pressure on the top of the cutting 80 member 15 to hold such cutting member in contact with the base member 12.

The rear edge of the cutting member 15 is provided about mid-way between its two ends with a notch 32, the approaches to 85 which are preferably beveled as at 33. The notch 32 is adapted for the reception of the inner end 34 of a driving member 35 the outer end of which is connected by a pivot 36 to the bottom 21 of the housing. 90

The plate 35 is provided with a longitudinally extending slot 37 for the reception of the bottom end of the eccentric driving shaft 7.

When the motor shaft 6 is rotated an eccentric movement will be imparted to the shaft 7 and the driving member 35 will be oscillated on its pivot 36 and will impart reciprocating motion to the cutting member 15 thus causing the teeth 16 to move across 95 the teeth 14 and cut hair that enters between such teeth.

The mechanism for imparting reciprocation to the cutting member 15 is entirely

housed thereby excluding hair and other foreign substances that might otherwise tend to collect in and around such mechanism.

Obviously changes in the precise form of 5 construction of my invention may be resorted to within the scope of the following claim:

What I claim is:

Apparatus of the class described comprising 10 a motor embodying a casing having an enlarged upper end and a cylindrical bearing at its lower end, a housing secured to the lower end of said casing, a base member carried by the housing, the forward end of the 15 base member tapering upwardly and serrated to provide cutting teeth, a cutting member reciprocable upon the base member with the inner and outer edges thereof beveled and engaging the base only at the beveled edges, teeth formed at the outer beveled edge of the cutting member, the inner beveled edge of the cutting member having a

V-shaped notch formed therein with a rectangular socket at the apex of the V-shaped notch and extending into the body of the cutting member, an arm pivoted at its inner end to said base member, spaced therefrom and having a tapering end terminating in a rectangular projection entering the V-shaped and rectangular socket notch and of 30 less dimensions than said notch, said arm having a longitudinal slot therein adjacent the swinging end thereof, a main shaft extending into the cylindrical bearing of the casing, and an eccentric shaft carried by the 35 main shaft extending into the arm slot for shifting the arm, the sides of the V-shaped notch adapted to be engaged by the sides of the pointed end of the arm to limit reciprocal movements of the blade. 40

In witness whereof, I hereunto subscribe my name this 10th day of February, A. D. 1919.

AUGUST J. CARLSON.
